(57) **CLAIM**

I claim the ornamental design for a tent pole, as shown and described.

DESCRIPTION

FIG. 1.1 is a perspective view of a tent pole showing my new design;

FIG. 1.2 is a front elevation view thereof;

FIG. 1.3 is a rear elevation view thereof;

FIG. 1.4 is a left side elevation view thereof;

FIG. 1.5 is a right side elevation view thereof;

FIG. 1.6 is a top plan view thereof;

FIG. 1.7 is a bottom plan view thereof;

FIG. 1.8 is an enlarged view showing a portion from FIG. 1.1;

FIG. 1.9 is an enlarged view showing a portion from FIGS. 1.2; and

FIG. 1.10 is an enlarged view showing entire elements of FIG. 1.7.

The dot-dash boundary lines shown in FIGS. 1.1-1.2 and 1.7-1.10 demarcate the boundary of the claimed area. The
